UNITED STATES PATENT OFFICE.

JAMES TRANTER AND CHARLES J. TRANTER, OF COVINGTON, KENTUCKY.

MEANS FOR CASTING STEEL INGOTS.

SPECIFICATION forming part of Letters Patent No. 241,758, dated May 17, 1881.

Application filed January 10, 1881. (No model.)

To all whom it may concern:

Be it known that we, JAMES TRANTER and CHARLES J. TRANTER, both of Covington, Kenton county, Kentucky, have jointly invented a new and useful means for Casting Steel Ingots, of which the following is a specification.

Our invention was originally designed and is more especially intended to facilitate and improve the manufacture of steel and semi-steel ingots under the Siemens - Martin, the Bessemer, and kindred processes.

The immense stimulus given to the manufacture of every form of steel, semi-steel, and even of iron, by the above processes has made it a matter of great commercial importance that the subsequent but scarcely less necessary processes of casting and subdivision of the ingots should be brought to the same perfection that the process of conversion has reached.

In order to secure density and homogeneity of metal, as well as to save pit-room and to bring a single run within easy control of one pitman and founder, it is customary to convey the molten steel from the ladle through a tall "runner" and a suitably gated bed into the lower ends of a compact assemblage of high vertical molds, the ingots produced in which are, at great expenditure of power and wear and tear of machinery and considerable waste of material, cut or severed into rough blocks or fragments approximating the desired weights. The defects of this mode of operation, which were less conspicuous under the comparatively slow and limited manufacture of steel by smelting, puddling, and cementation, have lately become manifest; but no practical solution of the problem has, to our knowledge, been heretofore suggested.

Among the more serious objections to the practice hitherto employed may be cited the great expenditure of power required to sever into fragments a slab of steel, sometimes a foot or more thick, by cutting either with the shears or chisel; the frequent breaking of the ponderous machinery employed for that purpose, which, beside the expenses of repair, involves the enforced idleness of one or more gangs of laborers during inaction of the machinery; the impossibility of producing billets having any

near approximation to the desired weight; the formation of fins and like jagged projections, which, in the subsequent processes of tilting, rolling, or forging, failing to fully weld or incorporate with the body of the billet, cause hidden faults and flaws.

Our improved means consists of the provision, in each mold, of a series of superimposed compartments separated by partitions secured horizontally within each mold, each partition being gated for passage of the molten steel, and being either composed of or coated with a refractory substance. The adherence of the component sections of each ingot cast in such mold is such as to keep each ingot intact for withdrawal from the mold, as well as for subsequent handling, storage, or shipment; but such also as, at any desired moment, to permit the ready separation of one or more component sections. Our system, while securing in a greater degree than heretofore the advantages of high vertical casting and of transportation intact, as already stated, enables each component section to be made compact and homogeneous throughout, of any desired symmetrical form and size, of a precise weight, and readily separable when desired.

In the accompanying drawings, Figure 1 is a partly sectioned elevation of a casting apparatus such as employed in our improved process. Fig. 2 is a perspective view of a mold. Fig. 3 represents two partitions and a cap-plate. Fig. 4 is a section, to a larger scale, through one of the partitions. Fig. 5 is a side elevation, partly in vertical section, of a partitioned ingot. Fig. 6 is a face view of a partition or boundary plate with designating marks. Fig. 7 represents the corresponding ingot-face.

A is a bed plate or slab, whose bottom and marginal portions, *a*, are preferably of cast-iron, and whose portion *b*, in contact with the molds and runner, and forming the walls of the conducting-passages of the molten metal, is of fire - tile or other refractory material. The bed-plate communicates, at or near its center, with the lower extremity of a tall vertical pipe, C, called the "runner," which is surmounted by a funnel, D. Both runner and funnel are lined with fire-clay E, or other refractory material. Numerous passages F in

the non-metallic portion of the bed-plate conduct from the foot of the runner to the lower extremities of as many vertical molds G, preferably of cast-iron, which molds taper slightly upward in the manner represented. Two of these molds are shown in the figure. Each mold has ears H for engagement of the crane-tackle for lifting of the respective molds to and from their places on the bed-plate. The taper form of the interior of the mold enables it to be readily withdrawn from the cast ingot after the latter has set. The tapering form of the mold interior also facilitates the insertion and temporary fixture of one or more horizontal partitions, J, which partitions constitute the distinguishing feature of our means for producing the partitioned ingots, whose manufacture is the ultimate object of our invention. Each partition has on its margin, as in Figs. 2 and 3, gates or passages j for ascent of the molten steel. Our partitions are either wholly or superficially of a refractory material, our preferred construction being a sheet, j', of thick sheet-iron—such as boiler-plate scraps coated, j'', with black-wash, plumbago, fire-clay, or other refractory substance.

In addition to the partitions J, embedded in the mold and constituting a part of our composite ingot, we preferably employ one or more end or boundary plates, J' J'', near the top of the mold. The plate or slab J' we designate the "cap." The cap J' has several important uses. It arrests the ebullition and deflagration of the rising body of molten metal, and in so doing prevents overflow and coacts with the pressure derived from the column of molten metal in the runner, to secure solidity and sharpness of form at the extreme summit of the ingot. It is also useful by separating from the ingot-body the overrun K, to enable its easy removal by chisel while the metal is still hot.

We also sometimes employ a similar plate, F'', called the "sole plate," for the more perfect separation of the ingot from the bed-plate, and smoother finish of the ingot-base.

Our above described and preferred means are susceptible of various modifications. For example, instead of wrought-iron the partitions may be composed of refractory semi-steel or cast-iron, and may have any desired letters, figures, or other distinguishing marks, either in raised form, as in Fig. 6, or in intaglio, so as to produce a corresponding reverse impression upon the contiguous billet-face, as in Fig. 7; or such characters may be impressed upon the wrought partitions by the die employed to form them from the boiler-scrap or other material.

While preferring to use our partitions J and boundary plate or plates J' J'' in the described connection with taper molds, we reserve the right to employ such partitions in molds of parallel walls having longitudinal partings clamped or keyed together, and suit-

able shoulders or recesses to hold the partitions.

The respective partitions and boundary or end plates being cut in a suitable die, or by other means formed to the proper dimensions, and being coated with fire-clay or other refractory substance, are forced into the mold, so as to become jammed tightly therein, as seen in Fig. 1. The molten steel, rising through the mold from one compartment to another, compactly fills all of the interstices and embeds the partitions in its substance. The dimensions of the mold and the specific gravity of the metal being known, the partitions may obviously be formed of such dimensions as to produce billets of the precise weight desired, and these billets may have suitable designatory marks, as indicated in Fig. 7. The said castings having become sufficiently set, their taper form and slight adhesion of their parts enable their easy withdrawal, with their accompanying partition-plates, and their removal for storage intact for any desired period.

When it is desired to detach one or more sections the separation is easily accomplished by a blow from a sledge or drop.

Mold-separating plates, as heretofore used at the ends of the molds or in open troughs, are less desirable than plates, ever so little, within the molds, on account of the liability to form locking overflows or fins.

The benefit of connecting the ingots by a small neck or sprue at one edge is the facility of separation after the partitions are removed by a simple blow without a cutting or a cleaving instrument.

The product herein described is claimed in another application of even date herewith.

We are aware that ingots have been cast in connected molds or divided troughs, and that U-plates have been inserted in slots in the mold sides for facilitating the chipping off of a piece of metal to ascertain its quality. Such modes of casting we do not therefore claim.

Our invention consists, as hereinbefore stated, in means for producing ingots subdivided by accompanying partitions.

Having thus described our invention, the following is what we claim as new therein and desire to secure by Letters Patent:

The combination, with a tall upwardly-tapered vertical mold for casting steel or semi-steel subdivided partitioned ingots, of one or more separable transverse gated plates composed of or faced with a refractory substance, and of such forms and dimensions as to fit tightly against the inside of the mold at any desired part or parts of its height, as and for the purposes set forth.

In testimony of which invention we hereunto set our hands.

JAMES TRANTER.
